US00D836133S

(12) **United States Design Patent** (10) Patent No.: **US D836,133 S**
 Silverstein et al. (45) Date of Patent: **** Dec. 18, 2018**

(54) **DISPLAY SCREEN WITH ICON**

(71) Applicant: **Seagate Technology LLC**, Cupertino, CA (US)

(72) Inventors: **Richard Silverstein**, San Francisco, CA (US); **Sarah Nguyen**, San Francisco, CA (US)

(73) Assignee: **Seagate Technology LLC**, Cupertino, CA (US)

(**) Term: **15 Years**

(21) Appl. No.: **29/549,941**

(22) Filed: **Dec. 29, 2015**

(51) LOC (11) Cl. **14-04**

(52) U.S. Cl.

USPC **D14/489**

(58) **Field of Classification Search**

USPC D14/485-495; D18/26, 31, 32, 33; D20/11, 12, 23, 24, 25, 29, 30, 31, 32, D20/36, 37, 38

CPC G06F 3/048; G06F 3/0481; G06F 3/0482; G06F 3/04817; G06F 3/04812

See application file for complete search history.
